LOOP TRANSFER MECHANISM FOR
KNITTING MACHINES

Alfred Percy Saunders, Leicester, England, assignor to Wildt and Company Limited, Leicester, England, a British company

Application March 15, 1957, Serial No. 646,480

Claims priority, application Great Britain March 16, 1956

19 Claims. (Cl. 66—24)

This invention appertains to knitting machines of the kind having two needle beds, and to loop transfer mechanism for use in such machines for effecting transference of knitted loops from the needles of one needle bed to those of the other needle bed during production of knitted fabric as and for purposes well known in the knitting art.

The invention, moreover, is applicable to two bed knitting machines wherein the stems of needles in either or both of the needle beds are made resilient so that the hooked portions of such needles can be deflected laterally either (a) to facilitate transference of knitted loops from the deflected needles to relevant receiving needles in the opposite bed, or (b) to enable the deflected needles to receive knitted loops from relevant transferring needles in the opposed bed.

So far as the transferring needles are concerned, these may, for instance, be of any of the forms disclosed in the specification of my prior United States Patent 2,249,080 and British Patents 520,417 and 535,162.

On the other hand such transferring needles may be of the improved form hereinafter to be described.

It is the intention to apply the invention to knitting machines of the kind concerned wherein the needles in one bed are moved transversely to those in the other bed. While, in this latter connection, the invention is principally intended for application to circular knitting machines of the cylinder and dial type, it may also be applied to straight bar machines having two needle beds relatively inclined to each other.

In prior loop transfer mechanism, the appropriate needles have customarily been deflected by contact with cam means. For instance, in certain previously proposed mechanisms, a deflector cam, arranged in such a way as to oppose a cam for advancing needles, is adapted when the needles are approaching the transferring position to engage the hooks thereof and thereby deflect the needles laterally. In another prior arrangement, deflector cam means are adapted to engage the outer longitudinal edges of the needles to be deflected.

Thus, as will be appreciated, in any arrangement employing deflector cam means, lateral deflection of needles is effected by a dragging action. Such means are accordingly inefficient on fine gauge knitting machines wherein, by reason of the close spacing of the needles, deflection by dragging is found to be insufficiently accurate.

The object of the present invention is to provide, in or for a knitting machine of the kind concerned, an improved, simple and efficient loop transfer mechanism designed to effect smooth, positive and accurate deflection of needles at greater machine speeds than have been possible heretofore.

Another object of the invention is to provide needle deflecting means which can be adjusted to a nicety.

The improved knitted loop transfer mechanism constituting this invention includes two co-axial spur gears which are rotatable together and are arranged to mesh

2

with needles in one needle bed of the machine at longitudinally spaced points along the stems of these needles, the two axially spaced co-axial gears being so set relatively that the teeth of the one are offset circumferentially with respect to the teeth of the other suchwise as to effect lateral deflection of the hooked portions of engaged needles advanced from the said bed.

The two co-axial gears are each furnished with the same number of teeth, which may vary.

10 The circumferential extent of the offset of the teeth of one gear with respect to those of the other corresponds to the lateral distance which the stems of the engaged needles are pushed aside by that gear which is disposed nearer to the heads of the needles.

15 As will be appreciated, were the teeth of two such co-axial gears to be arranged strictly in alignment, with the spaces between the teeth also aligned, both gears would mesh with the needles in the same way and no deflection would occur. But, by virtue of the two sets of gear teeth being relatively offset as described, the teeth of the gear nearest to the heads of the engaged needles "interfere" with the needle stems and push them aside.

20 This interference is a known factor directly related to the degree of the aforesaid circumferential offset of the relevant gear teeth. Accordingly, by making provision for relative angular adjustment of the two co-axial gears, the degree of the offset can be varied to produce a "measured interference" with the needle stems and hence

25 also a known and accurate lateral deflection of the needles so that either (i) the hooks of receiving needles in the opposing bed can with certainty be projected through, i. e., caused to penetrate, knitted loops held by the deflected (in this case transferring) needles, or (ii) the hooks of the deflected needles can be accurately positioned for receiving knitted loops from undeflected transferring needles in the opposing bed.

30 Of the two co-axial spur gears, one of them is arranged to be driven by the needles with which it meshes, whilst 40 the other, i. e., the needle interfering, gear is rotated from the said driven gear. Accordingly, as each needle in turn engages the rotating gears one side of the stem of the needle abuts against and is supported by a tooth of the driven gear, whilst the corresponding offset tooth of the interfering gear contacts the side of the needle and pushes the latter sideways, the deflection taking place from the point of support.

35 The appropriate side of each tooth of the interfering gear is so shaped, e. g., outwardly curved, as to avoid 45 presenting edges and marked protuberances to the needles, in this way smooth deflection of the engaged needles is ensured.

The two co-axial spur gears may conveniently be initially separate and so formed as to be adapted to provide, 50 when assembled together, a centrally bored unit for mounting upon an axle about which the gears are to rotate. In this case, two complementary formations on the respective interengaged gears may be so shaped as to provide for a limited degree of relative angular movement between the 55 two gears, and set screws provided in one of these formations may be arranged for contact with the other formation whereby the required degree to which the teeth of one gear are offset circumferentially with respect to the teeth of the other gear can be accurately determined and set.

60 In a convenient embodiment of the invention, the aforementioned axle about which the gears rotate is mounted in a bracket which is movable into and out of an operative position wherein the gears mesh with the needles in the appropriate bed. That is to say, whenever the said bracket 65 is moved into its operative position, the stems of the needles in the bed concerned will engage and push upon

the teeth of the driven gear and will, in turn, be contacted and pushed aside by the teeth of the associated interfering gear. Conversely, whenever the bracket is withdrawn to its inoperative position, the gears will be moved away from and clear of the needles—none of which will then be deflected. Thus, by suitable automatic control of the movements of the bracket, the needle deflecting gears can act on some or all of the needles in one of the needle beds. Thus, all of the needles of the set, or merely desired ones of such needles may be individually deflected 10 serially, according to loop transfer requirements.

Preferably, the bracket is spring controlled, being normally held out of its operative position against the spring action by a catch or the like and being releasable for movement into its operative position under the spring action by displacement of the said catch or the like. In such an arrangement, when the unit is in operation, the gears are capable of yielding outwardly, i. e., in a direction away from the engaged needle stems.

In order that the invention may be more clearly understood and readily carried into practical effect, a specific constructional example thereof embodying the foregoing and other features as applied to a circular knitting machine of the cylinder and dial type will now be described with reference to the accompanying drawings, wherein:

Figure 1 is a vertical sectional view of as much of the knitting head of the said machine as is necessary to illustrate the application of the invention thereto,

Figure 2 is a general perspective view of the two co-axial spur gears shown meshing with cylinder needles which are in the course of being raised by a transfer cam to transfer knitted loops to dial needles,

Figure 3 is a vertical sectional view taken through the gears but also, in chain lines, a portion of the bracket in which the gear axle is mounted,

Figure 4 is a detail perspective view of the two gears shown exploded fashion, prior to assembly,

Figure 5 comprises separated plan views of the two co-axial gears drawn in relation to a common centre line to show the relative setting of the said gears,

Figure 6 is a developed view, as seen from the inside of the cylinder cam box or shell, of two adjoining sections of the cylinder cam system of the knitting machine illustrated in Figure 1,

Figure 7 comprises underside plan views of two adjoining sections of the dial cam cap of the machine corresponding to the two cylinder cam sections illustrated in Figure 6,

Figures 8 and 9 are perspective front and rear views respectively of an improved form of transferring needle suitable for use in the cylinder of the said machine,

Figures 10 and 11 are two similar views showing a modification of this needle,

Figure 12 is a detail perspective view showing lateral deflection of the hooked portion of a cylinder needle during transference of a knitted loop from the latter to a dial needle,

Figure 13 is a somewhat similar detail perspective view but this time showing lateral deflection of a cylinder needle to facilitate transference of a knitted loop from a dial needle to the said cylinder needle, and

Figure 14 is a further detail perspective view of the co-axial gears as seen from the back, and shows more clearly the manner in which the hooked portion of a cylinder needle is laterally deflected for either of the purposes hereby described.

Like parts are designated by similar reference characters throughout the drawings.

In Figure 1, the stationary needle cylinder of the illustrated machine is indicated at 1 and the stationary dial at 2. The rotary cylinder cam box or shell and the rotary dial cam cap are depicted at 3 and 4 respectively. The numeral 5 indicates a cylinder needle and at 6 is shown a dial needle.

For advancing cylinder needles selectively, and so deter-

mining which of these needles is to be raised to transfer height during transference of knitted loops from the said needles to opposed dial needles, there is provided at a transfer station TS a needle selecting unit indicated generally at 7 in Figure 1. This well known type of unit, illustrated purely diagrammatically, comprises an intermittently rotatable drum furnished with pre-arranged pins or bits 8, and an associated bank of selectively actuated selector slides 9. These slides are arranged for action, according to patterning requirements upon appropriate butted elements 10 which are mounted in the cylinder tricks or grooves 1a in front of springy lower extensions 11a of jacks 11 provided for raising cylinder needles selectively at required times. At its lower extremity the springy extension 11a of each of the jacks 11 is formed with a butt 11b. Normally, the said springy extensions 11a are outwardly splayed away from the bottoms of the tricks or grooves 1a, so that their butts 11b are clear of jack-raising cams such as the raising cam 12 at the transfer station TS in Figure 6. However, as and when a selector slide 9 is pushed in by a drum pin or bit 8 so that it acts upon a butt 10a of an element 10, that particular element, and hence also the springy extension 11a with which it is associated, will be pressed in against the springy action suchwise as to displace the butt 11b of the relevant jack into the path of a jack-raising cam such as 12. Cylinder needles 5 corresponding to spring jacks 11 which are selectively raised at a transfer station TS will be elevated to an extent sufficient for their knitting butts 5a to be landed on to a transfer cam 13 provided in the transfer section 3a of the cylinder cam box or shell 3 (see Figure 6) by means of which cam the said needles are raised to the transfer height shown in Figure 12. The knitting butts 5a of non-selected cylinder needles, whose jacks 11 are not raised by the cam 12, pass beneath the transfer cam 13. Each of selected cylinder needles raised to transfer height as just described transfers a knitted loop such as that indicated at L in Figure 12 to an opposed dial needle 6. After being advanced to transfer height, cylinder needles are immediately retracted by engagement of their butts 5a with a depressor cam 14. To enable the relevant dial needles to receive loops from selected cylinder needles 5, all of such dial needles are partially advanced to the position shown in Figure 12 by engagement of their butts 6a with an outwardly shaped cam portion 15 of a cam track within a transfer section 4a of the dial cam cap 4 (see Figure 7).

It is also possible within the scope of this invention, to effect transference of knitted loops from dial needles 6 to cylinder needles. Indeed, in Figure 13 a loop L' is shown in the course of being so transferred. To enable such transference to take place, a transfer section 4a of the dial cam cap 4 is, as shown in Figure 7, fitted with a transfer cam 16 which, by action on butts 6b of the dial needles 6 advances the latter to the transfer position occupied by the particular dial needle depicted in Figure 13. After being advanced for this purpose the dial needles are thereupon immediately retracted to their original inoperative, i. e., withdrawn, positions by engagement of their butts 6a with a cam 17. To enable them to receive loops from dial needles, cylinder needles 5 are partially raised, to the height shown in Figure 13, by action of the cam 16, on their knitting butts 5a.

In either case, and in accordance with well known practice, retraction of a transferring needle immediately following advance thereof to a transfer position enables the loop being transferred to be left on the receiving needle.

It is convenient here to mention that in Figures 6 and 7 knitting sections of the cylinder cam box or shell 3 and the dial cam cap 4, adjoining the transfer sections 3a and 4a thereof, are indicated at 3b and 4b respectively.

Now whether knitted loops are to be transferred from

selected cylinder needles to relevant dial needles, or from dial needles to cylinder needles as hereinbefore described, it is necessary in either case for cylinder needles to be accurately deflected laterally in the first case to facilitate the transference of loops from the deflected cylinder needles to receiving dial needles, and in the second case to enable the deflected cylinder needles to receive loops from the transferring dial needles. Accordingly, the constructional example of the needle-deflecting means embodied in the loop transfer mechanism now to be described is associated with the stationary needle cylinder.

The said means, as illustrated more clearly in Figures 1-5, comprise co-axial spur gears 19 and 20 which are arranged to revolve about a vertical axle 21 set in suitably spaced upper and lower horizontal limbs 22a and 22b of a forked portion of a bracket 22. This bracket, as shown in Figures 1 and 2, is mounted for swivelling movement about a vertical fulcrum screw 23 screwed into the top of a transfer section 3a of the rotary cylinder cam box or shell 3. If desired, and as shown, the fulcrum screw 23 may be mounted in a block 24 which is combined with, and adjustable longitudinally with respect to, a horizontally extending base portion 22c of the swivelling bracket 22. In any event there is provided on the top of the bottom cam box section 3a, at the outer side of the bracket 22, an upstanding lug 25 tapped to receive an adjusting screw 26 (Figure 2) the inner leading end of which acts on a comparatively strong compression spring 27 interposed between the inner side of the lug 25 and the opposed outer side of the bracket 22. Whenever permitted, therefore, the bracket 22 swings inwards into its operative position under the influence of the compression spring 27. With the bracket 22 in this position, the teeth of the co-axial gears 19 and 20 mesh with the stems of the cylinder needles 5. By an adjustment of the screw 26 within the upstanding lug 25, the effective strength of the compression spring 27 can be varied to vary correspondingly, within fine limits, the depth to which the teeth of the gears 19 and 20 mesh with the needles 5. For turning the swivelling bracket 22 outwards away from the rotary cylinder 1, against the action of the compression spring 27, and thereby rendering the gears 19 and 20 inoperative, there is provided, as illustrated in Figures 1 and 2, a two-armed lever 28 which lies flat upon the top of the cylinder cam box section 3a and is mounted to turn about a fulcrum screw 29 screwed into the section. One arm 28a of this lever extends alongside the inner face of the base portion of the bracket 22, whilst the other arm 28b extends outwardly over the top and clear of the cylinder cam box or shell 3. Adjacent to the outwardly extending arm 28b of the lever 28, there is provided, also on the top of the cam box section 3a, a pivoted catch 30 having a nose 30a adapted to engage behind a pin 31 on the lever 28 for the purpose of locking the latter with the bracket in its withdrawn position. The pivoted catch 30 is arranged to turn about a fulcrum screw 32 which is screwed into the top of the cam box section 3a, and is influenced by a tension spring 33 one end of which is anchored to the catch 30 whilst the opposite end is similarly anchored to the outwardly extending arm 28b of the two-armed lever 28. Thus, whenever this lever is acted upon and turned to withdraw the swivelling bracket 22 against the action of the compression spring 27 the pivoted catch 30 will also be turned until its nose 30a snaps into position behind the pin 31. To release the bracket 22 and so permit the co-axial gears 19 and 20 to move into mesh with the needles 5, under the influence of the compression spring 27, the pivoted catch 30 is acted upon to trip it out of engagement with the pin 31. Intermediate connections of any suitable character, actuated at required times from a control unit are provided for action upon the lever 28 and the catch 30. A specific example of such connections will be hereinafter described.

The lower horizontal spur gear 19 which is to be driv-

en by the needles 5 is of small diameter, being furnished with twenty four or any other suitable number of regularly shaped involute teeth 19a. As depicted more clearly in Figure 3, the underside of the gear 19, which is centrally apertured as indicated at 34 in Figure 5, is formed with a shallow boss 19b which rests upon the lower horizontal limb 22b of the forked portion of the bracket 22. Projecting up from the flat top surface of the gear 19 is a segmental-shaped formation 19c. Also formed on the top of the driven gear 19 is a small lug 19d (Figures 4 and 5) which is spaced apart from the formation 19c and is tapped in the radial direction to receive a screw 35 used for a purpose presently to be described. The upper needle interfering gear 20 is also formed with twenty four deflector teeth 20a, but instead of each tooth being of normal involute form one of the sides of the tooth is cut back a little and nicely rounded, all as shown in Figure 5. The deflector teeth may, however, also be of involute form. Projecting down from the underside of the interfering gear 20 is an integral, mainly rectangular block 20b which, however, has rounded ends and is tapped as indicated at 20c at opposite sides of the axis of the gear to receive two adjustment screws 36. The vertical side face 20d of the block 20b through which face the leading ends of the adjustment screws 36 protrude when these are screwed in sufficiently far is not quite flat but slopes back slightly in opposite directions from the centre of the face as shown most clearly in Figure 5. Extending down from the bottom of the block 20b is a boss 20e which is concentric with the axis of the gear 20 and is centrally bored. The bore in the boss 20e continues upwards right through the block 20b and the superposed needle interfering gear 20 to receive the vertical axle 21. The end portions of the axle are located in aligned holes formed in the spaced horizontal limbs 22a and 22b of the forked portion of the bracket 22. When the driven and the interfering gears 19 and 20 are assembled together, the bored boss 20e projecting down from the interfering gear 20 is accommodated in the central aperture 34 in the driven gear 19, and the side face 20d of the block having the oppositely sloping surfaces opposes the flat inner face of the segmental-shaped formation 19c.

The fact that the said side face of the block is sloped back as described permits a limited degree of relative angular adjustment of the two gears. The relative disposition of the teeth 19a and 20a of the co-axial gears 19 and 20 is determined by appropriate adjustments of the two screws 36 in the block 20b, and these screws are used to set the gears in their adjusted positions relatively to each other. But by virtue of the pressure exerted by the screws 36 upon the segmental-shaped formation 19c, there is a tendency for the driven gear 19 to be pushed out of strict concentricity with respect to the needle-interfering gear 20. This tendency can be obviated, and the two gears restored to the necessary concentric condition, by screwing in the screw 35 so that it presses laterally upon the block 20b. The two gears 19 and 20 are freely rotatable about the axle 21 in the space between the two horizontal limbs 22a and 22b of the bracket 22. The top face of the upper, i. e., the needle-interfering, gear 20 is disposed in a horizontal plane just below the bits 38 of the cylinder verge.

The manner in which the gears 19 and 20 function to deflect the stems of cylinder needles 5 will be apparent from Figure 5. In this figure the chain line 39 is common to both of the separately shown gears 19 and 20, and by comparing the disposition of the teeth 19a with the disposition of the teeth 20a both in relation to this line it is possible to appreciate the degree to which the teeth of the one set are circumferentially offset with respect to the teeth of the other set. Thus, assuming the two gears to be rotating anti-clockwise as shown in Figure 5, the needle stem 5b, shown in cross-section, will be pushed aside to the right from, say, a position on the chain line 39 (where the said stem meshes with the teeth 19a of the driven gear 19) to a position at the right-hand

side of the line to which it is deflected by the tooth 20a' of the gear 20 nearest to the hook of the needle.

A typical extent to which the stem of a cylinder needle 5 is laterally deflected will also be appreciated by comparing the relative positions of teeth 19a and 20a with respect to the line 40 in each of Figures 12 and 13. Then again in Figure 14 the deflection of a needle is shown in relation to a vertical line 41.

In association with, and located above, the co-axial gears 19 and 20 just described, there may be provided, as shown in Figure 2, a fixed guide plate 42 an end portion 42a of which is adapted to hold down fabric whilst cylinder needles such as those indicated at 5¹, 5², 5³ and 5⁴ are being advanced to transfer their loops to dial needles 6. Towards its opposite end the plate 42 has thereon an outwardly protuberant or bulging cam surface 42b adapted to act upon the backs of the cylinder needles 5 suchwise as to cant these needles outwardly and enable them not only to clear the cylinder verge bits 38, but also to stretch and enlarge the knitted loops L, thereby enabling the hooks 6c of the receiving dial needles 6 to penetrate and receive the said loops. In this way, dial and cylinder needles are enabled to disengage from one another during a loop transferring operation, at the same time leaving transferred loops in the hooks of the relevant dial needles. The end portion of the plate 42 immediately adjoining the bulging cam surfaces 42b is recessed at 42c to permit the outwardly canted needles to move inwardly again. The portion 42d of the guide plate 42 between the portion 42a and the bulging surface 42b is of such a thickness as to enable advanced cylinder needles such as those indicated at 5⁵ and 5⁶ in Figure 2 to be back in their tricks. The guide plate 42 may conveniently be secured by screws 42 to the peripheral edge of the section 4a of the dial cap 4, provision being made for circumferential adjustment of the plate.

Now in loop transfer mechanisms of the kind concerned, the stem of each of the transferring needles is customarily recessed or relieved at one side to reduce the thickness of the needle and thereby facilitate lateral flexure thereof. Heretofore, the recess has extended transversely right across the full width of the needle. For the purpose of the present invention, however it is important that the full thickness of the front edge of the stem 5b of each cylinder needle 5 (which edge is engaged by the co-axial spur gears 19 and 20) shall be maintained throughout, thereby maintaining absolute accuracy of the lateral deflection of the needle. For this reason, and as shown more clearly in each of Figures 8 and 10, the fronts 44a of the recesses 44 in the sides of the cylinder needles stop short of the front edges of the latter so that only back portions of the needle stems immediately adjoining the rear edges are reduced in thickness as depicted in Figures 9 and 11.

The transfer cylinder needles may in appropriate cases be bowed or bulged laterally as represented at 5c (Figures 8 and 9) to provide clearance for the receiving dial needles 5 to enter the loops L to be transferred prior to receiving such loops. But in fine gauge machines where the extent of lateral deflection of the transfer needles can only be very small, it is preferred that the appropriate portion 5a of the stem 5b of each of needles 5 shall be flat at one side (see Figure 10) in which instance the required clearance for a receiving dial needle is provided by recessing the opposite side of the stem as illustrated at 5e in Figure 11 so that the thickness of the front edge of the stem is maintained and the deepest part of the recess immediately adjoins the rear edge of the stem which is straight in contra-distinction to being bowed.

The means and the connections for actuating and controlling the lever 28 and the associated catch 30 will now be described with reference to Figure 1. In this figure it will be seen that there is provided at a relatively fixed location on the outside of the rotating cam box structure of the machine, an intermittently rotatable control drum

45. This drum is fitted with rows of prearranged pegs 46 which are located in two horizontal planes occupied also by a pair of superimposed strikers 47 and 48. These strikers, which may conveniently be spring influenced or equivalently biassed, are represented in purely diagrammatic fashion and without the comb provided for supporting and guiding them. They may, for instance, consist of slide-levers. In any event, the lower striker 47 is provided for striking the arm 28b of the lever 28, whilst the upper striker 48 is for similar action upon the pivoted catch 30. The strikers are acted upon directly by the drum pegs 46, and are themselves adapted for action directly upon the lever 28 and the catch 30.

The control drum 45 is arranged to be driven, one or more racks at a time, according to patterning requirements, from the rotating cam box structure at the dictates of a timing chain 49 furnished with studs 50. There is secured to the bottom of the drum 45 a ratchet wheel 51 arranged to co-operate with a pawl 52. The said pawl is pivotally mounted upon a lever 53 arranged for oscillatory motion about the vertical axis 54. For imparting operative strokes to the lever 53 through the medium of a further lever 55 rigidly connected therewith, there is provided a continuously reciprocable slide 56 furnished with a roller 57 which is acted upon by a cam 58 carried by the rotating cam box structure. The lever 55 carries an adjustable abutment screw 59 for contact by the slide 56. But although the slide reciprocates continuously, the lever 55, and hence also the pawl lever 53, are normally held quiescent by a latching lever 60. Thus, with the operative nose 60a of the latching lever 60 normally in engagement with a catch-piece 61 combined with the lever 55, the pawl 52 is held inoperative and prevented from racking round the drum 45. The catch-piece 61 is, however, displaceable by each of a series of the studs 50 on the timing chain 49. Whenever the catch-piece is displaced in this way to disengage it from the latching lever 60, the lever 55 is released to be acted upon by the slide 56 as a consequence of which an operative, i. e., forward, stroke is imparted to the pawl 52 and the drum 45 is, therefore, racked round to the extent of one step. As, however, the pawl lever makes its reverse stroke, the latching lever 60 automatically re-engages the catch-piece 61. Accordingly, a succession of racks of the control drum 45 can only be achieved by a succession of chain studs 50 acting on the catch-piece 61 seriatim.

I claim:

1. In a knitting machine, in combination, two opposed needle beds, knitting needles operating in said beds, the needles in at least one of said beds having stems which are flexible to the extent of permitting of lateral deflection of the hooked portions of said needles when knitted loops are being transferred from the needles of one bed to those of the opposed bed, means for advancing the needles having flexible stems from the relevant bed during such a transference of loops, and two co-axial spur gears which are rotatable together and are adapted to mesh with said flexible needles at longitudinally spaced points along the stems thereof, the said two gears being so set relatively that the teeth of the one are offset circumferentially with respect to the teeth of the other suchwise as to effect lateral deflection of the hooked portions of engaged needles advanced from the said relevant bed.

2. A combination according to claim 1, wherein the said two co-axial gears are each furnished with the same number of teeth.

3. A combination according to claim 1, which includes means for angularly adjusting the said two co-axial gears whereby the degree of the circumferential offset of the relevant gear teeth can be varied to produce a known lateral deflection of the appropriate needles.

4. In a knitting machine, in combination, two opposed needle beds, knitting needles operating in said beds, the needles in at least one of said beds having stems which are flexible to the extent of permitting of lateral deflec-

tion of the hooked portions of said needles, when knitted loops are being transferred from the needles of one bed to those of the opposed bed, means for advancing the needles having flexible stems from the relevant bed during such a transference of loops, and two co-axial spur gears arranged to mesh with the flexible needles at longitudinally spaced points along the stems thereof, the said two gears being so set relatively that the teeth of the one are offset circumferentially with respect to the teeth of the other so that the offset teeth interfere with the stems of the said flexible needles, and the said needle interfering gear being rotated from the companion gear which latter is driven by the needles with which it meshes, the arrangement being such that as each advancing flexible needle, during transference of knitted loops engages the rotating gears one side of the stem of such needle abuts against and is supported by a tooth of the driven gear whilst the corresponding offset tooth of the interfering gear contacts the said needle and pushes the latter sideways, the deflection taking place from the point of support.

5. A combination according to claim 4, wherein the appropriate side of each offset tooth of the needle interfering gear is so cut back and outwardly curved as to avoid presenting edges and protuberances to the flexible needles.

6. A combination according to claim 4, including a bracket furnished with an axle upon which the two co-axial gears are mounted for rotation.

7. A combination according to claim 6, wherein the bracket is movable into and out of an operative position in which the gears mesh with the flexible needles in the appropriate bed so that whenever the bracket is moved into its operative position the stems of the flexible needles will engage and push upon the teeth of the driven gear and will be contacted and pushed aside by the offset teeth of the needle interfering gear, whereas whenever the bracket is withdrawn to its inoperative position the gears will be moved away and clear of the needles none of which will then be deflected.

8. A combination according to claim 7, wherein the bracket is spring controlled, being normally held out of its operative position against the spring action by a catch and being releasable for movement into its operative position under the spring action by displacement of the said catch.

9. A combination according to claim 8, wherein the bracket is controlled by a compression spring and is mounted for swivelling movement upon a part provided with a protuberance housing an adjusting screw, this screw acting on the compression spring and the latter being interposed between the protuberance and the bracket so that by an adjustment of the screw the strength of the compression spring can be varied to vary correspondingly the depth to which the teeth of the gears mesh with needles.

10. For use in a knitting machine of the kind herein referred to equipped with means for effecting transference of knitted loops from needles in one needle bed to needles in the opposed needle bed, a gear unit comprising two co-axial spur gears which are rotatable together and are adapted to mesh with needles in one of such beds, the said two gears being so set relatively that the teeth of the one are offset circumferentially with respect to the teeth of the other, for the purpose herein described.

11. A gear unit according to claim 10, wherein one of the gears has regularly shaped involute teeth, and the other gear is furnished with teeth each of which has one of its sides cut back and rounded.

12. A gear unit according to claim 10, wherein the two co-axial gears are initially separate and are so formed as to provide, when assembled together, a unit which is centrally bored.

13. A gear unit according to claim 12, wherein two co-operating formations on the respective assembled gears are so shaped and dimensioned as to provide for a limited degree of relative angular movement between the two gears, and screws provided in one of the said formations are arranged for contact with the other formation in such a way that by adjustment of the screws, the degree to which the teeth of one gear are offset circumferentially with respect to the teeth of the other gear can be varied.

10 14. A gear unit according to claim 13, wherein one of the gears is centrally apertured and provided with a projecting segmental-shaped formation having an inner flat face, and the other gear is furnished with a block tapped at opposite sides of the axis of the gear to receive two adjustment screws, the face of the block through which the leading ends of the said screws protrude when they are screwed in sufficiently far sloping back in opposite directions from the centre of said face and opposing the inner flat face of the segmental-shaped formation, and the said block being combined with a bored boss which is accommodated in the central aperture in the first mentioned gear.

15. In a circular knitting machine, in combination, a cylinder, needles working in said cylinder, an associated dial, needles working in said dial, said cylinder needles being transfer needles having stems which are flexible to the extent of permitting lateral deflection of hooked portions of said needles, cam means associated with the cylinder for advancing cylinder needles to transfer height and thereafter retracting the same, other cam means associated with the dial for partially advancing dial needles to receive knitted loops from advanced cylinder needles as the latter are retracted, and two co-axial spur gears which are rotatable together and are adapted to mesh with cylinder needles at longitudinally spaced points along the stems thereof, the said two gears being so set relatively that the teeth of the one are offset circumferentially with respect to the teeth of the other so as to effect lateral deflection of the hooked portions of the engaged cylinder needles as these are advanced to transfer knitted loops thereon to dial needles.

16. A combination according to claim 15, which includes a guide plate a portion of which is adapted to hold down fabric whilst cylinder needles are being advanced to transfer loops to dial needles.

17. A combination according to claim 16, wherein the said guide plate has thereon a protuberant cam surface adapted to act upon the cylinder needles suchwise as to cant these needles outwardly and thereby stretch and enlarge knitted loops thereon for easy penetration by receiving dial needles.

18. In a circular knitting machine, in combination, a cylinder, needles working in said cylinder, an associated dial, needles working in said dial, said dial needles being transfer needles and the stems of the cylinder needles being flexible to the extent of permitting lateral deflection of hooked portions of said cylinder needles, cam means associated with the dial for advancing dial needles to transfer position and thereafter retracting the same, other cam means associated with the cylinder for partially advancing cylinder needles to receive knitted loops for advanced dial needles as the latter are retracted, and two co-axial spur gears which are rotatable together and are adapted to mesh with cylinder needles at longitudinally spaced points along the stems thereof, the said two gears being so set relatively that the teeth of the one are offset circumferentially with respect to the teeth of the other so as to effect lateral deflection of the hooked portions of the engaged cylinder needles and thereby prepare them to receive knitted loops from dial needles.

19. In a circular knitting machine, in combination, a cylinder, a set of needles working in said cylinder, said cylinder needles having stems which are flexible to the extent of permitting lateral deflection of hooked portions of said needles, a dial, a set of needles working in said

11

dial, cam means associated both with the cylinder and the dial for advancing and retracting cylinder and dial needles during transference of knitted loops from the needles of one set to needles of the other set, two co-axial spur gears which are rotatable together and are adapted to mesh with cylinder needles at longitudinally spaced points along the stems thereof, the said two gears being so set relatively that the teeth of the one are offset circumferentially with respect to the teeth of the other so as to effect lateral deflection of the hooked portions of the engaged cylinder needles and thereby facilitate transference of knitted loops as aforesaid, a swivelling bracket, an axle carried by said bracket and about which the said co-axial gears rotate, said bracket being turnable

12

into and out of an operative position in which the gears mesh with the cylinder needles, a spring controlling the bracket and urging it towards the cylinder, a lever for turning the bracket outwardly away from the cylinder 5 against the spring action, a catch for engaging said lever in the position required for holding the bracket in its in-operative position, movable strikers for actuating the lever and the catch, a rotary unit from which the strikers are controlled, means operated from the machine for racking 10 round the said control unit a step at a time, and a timing member dictating the times when the said unit is racked.
